The ornamental design for an automobile body, as shown and described.

DESCRIPTION

FIG. 1 is a left side view of an automobile body according to our novel design;

FIG. 2 is a front view of the automobile body of FIG. 1 according to our novel design;

FIG. 3 is a rear view of the automobile body of FIG. 1 according to our novel design;

FIG. 4 is a top view of the automobile body of FIG. 1 according to our novel design;

FIG. 5 is a perspective left side view from the top and the front of the automobile body of FIG. 1 according to our novel design; and,

FIG. 6 is a perspective view from the top and the rear of the left side of the automobile body of FIG. 1 according to our novel design.

The broken line showing of certain features, including the side mirrors, wheels, and fueling opening are only for showing the surrounding environment and are not a part of the claimed design.
